[57] **CLAIM**

The ornamental design for the combined alarm and illuminator for infrared detectors, as shown and described.

DESCRIPTION

FIG. 1 is a front view of a combined alarm and illuminator for infrared detectors showing my new design;

FIG. 2 is a rear view of the combined alarm and illuminator for infrared detectors;

FIG. 3 is a left side view of the combined alarm and illuminator for infrared detectors;

FIG. 4 is a right side view of the combined alarm and illuminator for infrared detectors;

FIG. 5 is a top view of the combined alarm and illuminator for infrared detectors;

FIG. 6 is a bottom view of the combined alarm and illuminator for infrared detectors;

FIG. 7 is a perspective top view of the combined alarm and illuminator for infrared detectors; and,

FIG. 8 is a perspective bottom view of the combined alarm and illuminator for infrared detectors.
